(57) **CLAIM**

The ornamental design for a manipulator, as shown and described.

DESCRIPTION

FIG. 1 is a perspective view of a manipulator showing my design, the manipulator including a movable arm in a first position;

FIG. 2 is similar to FIG. 1, but viewed from another aspect;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the manipulator in FIG. 1, the movable arm in a second position;

FIG. 10 is a perspective view of the manipulator in FIG. 1, the movable arm in a third position;

FIG. 11 is a perspective view of the manipulator in FIG. 1, the movable arm in a fourth position; and,

FIG. 12 is a perspective view of the manipulator in FIG. 1, the movable arm in a fifth position.

The broken lines in FIGS. 1 through 12 are included for the purposes of illustrating environment only and form no part of the claimed design.
